SILENCER FOR GAS-ENGINES, &c.

1,114,702.

Specification of Letters Patent.

Patented Oct. 20, 1914.

Application filed May 6, 1914. Serial No. 836,740.

To all whom it may concern:

Be it known that I, HIRAM PERCY MAXIM, a citizen of the United States, residing at Hartford, in the county of Hartford and 5 State of Connecticut, have made a certain new and useful Invention Relating to Silencers for Gas-Engines, &c., of which the following is a specification, taken in connection with the accompanying drawing, which 10 forms part of the same.

This invention relates especially to silencers for gas engines used in motor boat or other marine work and may comprise a bolted sectional casing of cast iron or the like, 15 each section having a substantially cylindrical casing body and an integral end or diaphragm which may be provided with a substantially central fluid aperture. A series of interchangeable cast iron diaphragms 20 having integral spiral guides may be fitted within the casing to form a series of silencing whirl chambers preferably of greater capacity adjacent the inlet end of the silencer. The alternate intermediate diaphragms are preferably provided with alternating central and narrow peripheral apertures next to the casing to form liquid 25 throttling apertures for the exhaust gases to promote the cooling and noise silencing 30 action.

In the accompanying drawing which shows in a somewhat diagrammatic way an illustrative embodiment of this invention, Figure 1 is a longitudinal section taken substantially along the line 1—1 of Fig. 2. Fig. 2 is a transverse section taken substantially along the line 2—2 of Fig. 1. Fig. 3 is a similar section along the line 3—3 of Fig. 1; and Fig. 4 is a detail elevation showing 40 several of the intermediate diaphragms and interlocking parts.

The silencer casing may be conveniently made in a series of sections of suitable material such as cast iron which is desirable 45 for use in gas engine silencers for motor boat or other marine work because of the relatively slight rusting action of salt water thereon. The casing sections may be formed with substantially cylindrical casing bodies 50 such as 2, with which the casing end or diaphragm 1 may be cast integral if desired, and also formed with a substantially central fluid aperture such as the gas inlet 3 for convenient connection with the gas en-

gine exhaust. If desired also a separate 55 inlet 43 may be provided at any convenient point for the separate admission of cooling liquid, although this is not of course necessary in all cases. The casing sections may be fastened together by any suitable means, 60 such as the fastening bolts 6 and cooperating nuts 7, which may pass through suitable fastening lugs, such as 4, 5, on the casing bodies which may thus be formed for convenient casting in green sand without 65 the use of cored work. Where as in the illustrated form only two casing sections are employed the casing body 27 may have cast integral therewith if desired the casing end 8 in which a suitable fluid aperture, such 70 as the gas and water outlet 9, may be arranged. In this way a strong and effective silencer casing may be cheaply provided which can be readily varied in length and internal capacity by substituting different 75 lengthened sections to the extent desired or by interposing suitable open cylindrical extension sections in an obvious manner.

A series of silencer chambers may be formed within the casing by fitting therein 80 a series of interchangeable diaphragms which may with advantage be formed of cast iron and provided with integral spiral guides extending laterally therefrom and given any suitable contour and size so as to 85 exert the desired silencing action on the gas impulses and sound waves of the engine exhaust. By making these diaphragms interchangeable any suitable number and style of diaphragms and guides may be used in 90 the casing to suit the particular engine requirements and it is usually of advantage to have one or two initial chambers adjacent the gas inlet of somewhat greater capacity or longitudinal length so as to more effectively take care of the greater volume of 95 gas because of its greater heat at the time of admission. It is also of advantage to have the alternate diaphragms provided with alternating central and narrow peripheral apertures which may with advantage be formed next the casing so as to provide liquid throttling apertures for the exhaust gases to enable the cooling liquid to have the desired effective cooling and sound throttling action as the gases pass through these relatively narrow slots or apertures.

The diaphragm 14 for the initial chamber

12 may be formed with the integral substantially cylindro-spiral guide 11 extending therefrom into substantial contact with the end diaphragm 1 of the casing so that the 5 exhaust gases are received into the central portion of this chamber and guided outward in a spiral path and then allowed to circulate around and around in the whirl chamber provided outside the end 13 and 10 outer surface 10 of this guide. In this way the kinetic energy of the exhaust gases is more or less dissipated and a desirable silencing action on the sound waves is also effected. Another diaphragm, such as 18, 15 forming the second silencing chamber 25, may be provided with a generally similar cylindro-spiral guide, such as 16, all of 20 these guides preferably extending in the same direction from the diaphragms substantially around the axis of the casing and diaphragm, although they may of course have greater or less angular extent in some cases. The diaphragm 24 is shown 25 as formed with the similar spiral guide 34 thereon and the final diaphragm 19 is shown as having the spiral guide 31 formed thereon in generally similar way as is indicated in greater detail in Fig. 3. The alternate intermediate diaphragms may be provided 30 with alternating central apertures, such as 17, 20 and narrow peripheral apertures, such as 22, which as indicated in Fig. 2 may be of substantially equal width throughout the circumference of the diaphragm and extend between suitable alining lugs 15 arranged at intervals to engage the inside of the casing. These peripheral apertures are adapted to have a desirable throttling noise silencing action in 35 connection with the cooling liquid employed which is carried around by the gases so as to act as a liquid curtain or shutter momentarily closing one or more of these apertures which are in series so as to greatly 40 promote the silencing of the noise of the exhaust. These diaphragms and guides may be conveniently held in alinement by suitable interlocking parts, such as the slot 45 23, with which the interlocking lug 28 on 50 the adjacent member may coöperate as seen in Fig. 2 so as to prevent accidental displacement or angular movement of these parts.

In the use of this silencer on a gas engine 55 the exhaust gases which are admitted to the silencer casing through the gas inlet 3 pass into the central portion or compartment of the initial chamber 12 and are given a spiral movement as they are guided 60 outward in the direction of the arrows in Fig. 2 so as to whirl around this initial chamber outside of the spiral guide. The simultaneously admitted cooling water or other liquid which may be fed into the 65 initial chamber through the water inlet 43

or which is previously present therein is swept around the chamber by the strong current or blast of the gases passing beneath the end 13 of the spiral guide adjacent the bottom of the casing. Thus the water is swept around the entire interior of the casing and more or less disseminated into drops so that it tends to more evenly cover the narrow peripheral apertures and act as a liquid curtain or shutter momentarily closing these slots or apertures and preventing the free passage of the sound wave therethrough so as to have an important silencing action especially where the sound must pass successively through a series of these liquid throttled apertures. The exhaust gases after passing into the second chamber 25 circulate around it as indicated by the arrows because of the spiral guide located therein and finally pass from the compartment 29 of this chamber through the central aperture 17 in the diaphragm 18 so as to enter the central compartment 30 of the third chamber 26. The gases are there given a similar whirling motion by the spiral guide 34 preferably also having its outer edge 32 adjacent but somewhat removed from the interior of the casing so as to form a similar whirl chamber outside the guide. The gases which have by this time been considerably reduced in temperature and in volume then pass through the narrow peripheral apertures in the diaphragm 24 so as to enter the fourth chamber 27 which in this instance is the last one used, although it is of course understood that a greater or less number of chambers may be employed, some three to six or seven giving good results with most small gas engines and providing ample capacity in each of the chambers which seems desirable in order to give more effective silencing action. The gases are guided as indicated by the arrows around the spiral guide 31 in this chamber so as to issue from the central aperture 20 communicating with the exhaust aperture or connection 9 in the casing, through which the entrained water may also be discharged if desired. The sharp impulses in the original engine exhaust have in this way been very largely smoothed and evened out and the volume of gases is also considerably reduced by the cooling action of the circulating water or other cooling liquid and also by the contact of the gases and liquid with the silencer casing throughout substantially all parts of its length which considerably promotes the dissipation of heat. The gases thus issue at such pressure and in such condition as to be free from objectionable noise on issuing from the silencer and the sound waves which constitute the objectionable noise of the original gas engine exhaust have been substantially dissipated or eliminated by the action of the series of whirl chambers

and water throttled apertures interposed in the course of the gases within the silencer.

This invention has been described in connection with a number of illustrative embodiments, forms, proportions, materials, constructions, numbers and arrangements of parts, to the details of which disclosure the invention is not of course to be limited, since what is claimed as new and what is desired to be secured by Letters Patent is set forth in the appended claims.

I claim—

1. The silencer adapted for use with gas engines and the like, comprising a bolted sectional cast iron casing, each section having a substantially cylindrical casing body and an integral end diaphragm provided with a substantially central fluid aperture, a series of interchangeable cast iron diaphragms having integral cylindro-spiral guides extending in the same direction therefrom and fitted in series within said casing to form a series of silencing chambers of greater capacity adjacent the inlet end of the casing, said spiral guides each extending substantially around the casing axis and terminating a considerable distance inside said casing to provide whirl chambers outside said guides, the alternate intermediate diaphragms being provided with alternating central and narrow peripheral apertures next to the casing to form liquid throttling apertures for the exhaust gases, there being alining lugs on said diaphragms in which the peripheral apertures are provided and interlocking slots and projections on said diaphragms and guides to maintain angular alinement between them.

2. The silencer adapted for use with gas engines and the like, comprising a sectional cast iron casing, each section having a substantially cylindrical casing body and an integral end diaphragm provided with a substantially central fluid aperture, a series of interchangeable cast iron diaphragms having integral cylindro-spiral guides extending in the same direction therefrom and fitted in series within said casing to form a series of silencing chambers of greater capacity adjacent the inlet end of the casing, said spiral guides terminating a considerable distance inside said casing to provide whirl chambers outside said guides, the alternate diaphragms being provided with alternating central and narrow peripheral apertures next to the casing to form liquid throttling apertures for the exhaust gases, there being alining lugs on said diaphragms in which the peripheral apertures are provided.

3. The silencer adapted for use with gas engines and the like, comprising a sectional cast iron casing, each section having a substantially cylindrical casing body and an integral end diaphragm, a series of interchangeable cast iron diaphragms having in-

tegral cylindro-spiral guides fitted in series within said casing to form a series of silencing chambers of greater capacity adjacent the inlet end of the casing, said spiral guides terminating a considerable distance inside said casing to provide whirl chambers outside said guides, the alternate diaphragms being provided with alternating central and narrow peripheral apertures next to the casing to form liquid throttling apertures for the exhaust gases.

4. The silencer adapted for use with gas engines and the like, comprising a sectional cylindrical cast iron casing, a series of interchangeable cast iron diaphragms having integral cylindro-spiral guides extending in the same direction therefrom and fitted in series within said casing to form a series of silencing chambers of greater capacity adjacent the inlet end of the casing, said spiral guides each extending at least substantially around the casing axis and terminating a considerable distance inside said casing to provide whirl chambers outside said guides, the alternate diaphragms being provided with alternating central and narrow peripheral apertures next to the casing to form liquid throttling apertures for the exhaust gases, there being alining lugs on said diaphragms in which the peripheral apertures are provided and interlocking slots and projections on said diaphragms and guides to maintain angular alinement between them.

5. The silencer adapted for use with gas engines and the like, comprising a sectional cylindrical cast iron casing, a series of interchangeable cast iron diaphragms having spiral guides and fitted in series within said casing to form a series of silencing chambers of greater capacity adjacent the inlet end of the casing, said spiral guides each extending at least substantially around the casing axis and terminating a considerable distance inside said casing to provide whirl chambers outside said guides, the alternate diaphragms being provided with alternating central and narrow peripheral apertures next to the casing to form liquid throttling apertures for the exhaust gases, and interlocking slots and projections on said diaphragms and guides to maintain angular alinement between them.

6. The silencer adapted for use with gas engines and the like, comprising a sectional cylindrical casing, a series of interchangeable diaphragms having spiral guides and fitted in series within said casing to form a series of silencing chambers of greater capacity adjacent the inlet end of the casing, said spiral guides each extending at least substantially around the casing axis, the alternate diaphragms being provided with alternating central and narrow peripheral apertures next to the casing to form liquid throttling apertures for the exhaust gases.

7. The silencer adapted for use with gas engines and the like, comprising a casing, a series of interchangeable diaphragms having spiral guides and fitted in series within 5 said casing to form a series of silencing chambers, the alternate diaphragms being provided with alternating central and narrow peripheral apertures next to the casing to form liquid throttling apertures for the 10 exhaust gases.
8. The silencer adapted for use with gas engines and the like, comprising a substantially cylindrical casing, a series of interchangeable diaphragms having integral 15 curved guides extending in the same direction therefrom and fitted in series within said casing to form a series of silencing chambers of greater capacity adjacent the inlet end of the casing, said guides each extending substantially around the casing axis and terminating a considerable distance inside 20 said casing to provide whirl chambers outside said guides, the diaphragms being provided with alternating central and narrow peripheral apertures next to the casing to 25 form liquid throttling apertures for the exhaust gases.
9. The silencer adapted for use with gas engines and the like, comprising a casing, 30 a series of diaphragms having curved guides extending in the same direction therefrom and fitted in series within said casing to form a series of silencing chambers, said guides terminating a considerable distance 35 inside said casing to provide whirl chambers outside said guides, the diaphragms being provided with alternating central and narrow peripheral apertures next to the casing to 40 form throttling apertures for the exhaust gases.
10. The silencer adapted for use with gas engines and the like, comprising a casing, a series of diaphragms having curved guides fitted in series within said casing to form a 45 series of silencing chambers, said guides terminating a considerable distance inside said casing to provide whirl chambers outside said guides, the diaphragms being provided with central and narrow peripheral apertures 50 to form throttling apertures for the exhaust gases.
11. The silencer adapted for use with gas engines and the like, comprising a sectional cast iron casing each section having a substantially cylindrical casing body and an 55 integral end diaphragm, a series of interchangeable cast iron diaphragms having integral cylindro-spiral guides extending in the same direction therefrom and fitted in series within said casing to form a series of silencing chambers of greater capacity adjacent the inlet end of the casing, said spiral 60 guides each extending substantially around the casing axis and terminating a considerable 65 distance inside said casing to provide
- whirl chambers outside said guides, the alternate intermediate diaphragms being provided with alternating central and narrow peripheral apertures next to the casing to form liquid throttling silencing apertures 70 for the exhaust gases.
12. The silencer adapted for use with gas engines and the like, comprising a sectional cast iron casing each section having a substantially cylindrical casing body and an 75 integral end diaphragm, a series of interchangeable cast iron diaphragms having spiral guides extending in the same direction therefrom and fitted in series within said casing to form a series of silencing 80 chambers of greater capacity adjacent the inlet end of the casing, the alternate intermediate diaphragms being provided with alternating central and narrow peripheral apertures next to the casing to form liquid 85 throttling silencing apertures for the exhaust gases.
13. The silencer adapted for use with gas engines and the like, comprising a sectional cast iron casing each section having a substantially cylindrical casing body and an 90 end diaphragm, a series of interchangeable cast iron diaphragms having spiral guides extending in the same direction therefrom and fitted in series within said casing to 95 form a series of silencing chambers, the alternate diaphragms being provided with alternating central and narrow peripheral apertures next to the casing to form silencing 100 apertures for the exhaust gases.
14. The silencer adapted for use with gas engines and the like, comprising a sectional casing each section having a substantially cylindrical casing body and an end diaphragm, a series of interchangeable diaphragms having spiral guides extending in the same direction therefrom and fitted in series within said casing to form a series of silencing chambers, the alternate diaphragms being provided with alternating 105 central and peripheral apertures next to the casing to form silencing apertures for the 110 exhaust gases.
15. The silencer adapted for use with gas engines and the like, comprising a substantially cylindrical sectional cast iron casing provided with a substantially central fluid aperture, a series of interchangeable substantially flat cast iron diaphragms having integral cylindro-spiral guides extending in 115 the same direction therefrom and fitted in series within said casing to form a series of silencing chambers of greater capacity adjacent the inlet end of the casing, the alternate intermediate diaphragms being provided with alternating central and narrow 120 peripheral apertures next to the casing to form silencing apertures.
16. The silencer adapted for use with gas engines and the like, comprising a substan- 125

tially cylindrical casing provided with a substantially central fluid aperture, a series of interchangeable substantially flat dia-
phragms having spiral guides extending in the same direction therefrom and fitted in series within said casing to form a series of silencing chambers, the alternate dia-
phragms being provided with alternating

central and narrow peripheral apertures next to the casing to form silencing apertures.

HIRAM PERCY MAXIM.
